UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

GAS-REGULATING VALVE.

1,319,782.

Specification of Letters Patent. Patented Oct. 28, 1919.

Application filed April 9, 1919. Serial No. 288,776.

To all whom it may concern:

Be it known that I, HENRY C. MAUL, a citizen of the United States of America, residing at Detroit, in the county of Wayne 5 and State of Michigan, have invented certain new and useful Improvements in Gas-Regulating Valves, of which the following is a specification, reference being had therein to the accompanying drawings.

0 My invention aims to provide a gas regulating valve which has a wide range of action by being adjustable to meet requirements with either high or low pressure artificial or natural gas, and particularly low 5 pressure natural gas. It is in this connection that my invention aims to provide simple means whereby the velocity of gas and its volume may be separately regulated to give a proper combustion under all pressure conditions and in accomplishing this result I preclude any danger of back flash and eliminate noise incident to the discharge of gas from the nipple of the valve particularly when the gas is under high pressure.

To burn gas for heating purposes, it must be mixed with oxygen before it leaves the orifices or ports of a burner, and this is accomplished by having a jet of gas pass through a tube of larger diameter than the jet at a point where it leaves the orifice and since different qualities of gas require different proportions of oxygen, the greater the velocity of the jet of gas through the tube, the greater the amount of oxygen that will be injected and commingle with the gas. Then again, since the velocity of the gas depends upon the pressure thereof, it is obvious that when the velocity is increased, it will inject too much air or oxygen and will make the mixture too lean or thin to burn. In view of these facts, I have devised a valve embodying a velocity or regulating chamber and a volume or jet regulating chamber said chambers being so arranged as to be easily adjusted, whereby the volume, pressure, velocity and air injecting powers may be minutely regulated.

My invention will be better understood when reference is had to the drawing and the detail construction thereof, showing one embodiment of my invention which has been thoroughly tested under artificial and natural gas conditions, and found very satisfactory, yet I do not care to confine my in-

vention to the precise construction and arrangement of parts other than defined by the appended claims. 55

In the drawings,

Figure 1 is a longitudinal sectional view of a gas regulating valve in accordance with my invention; showing the valve on a larger scale than actually used; 60

Fig. 2 is a cross sectional view taken on the line II—II of Fig. 1; and

Fig. 3 is a similar view taken on the line III—III of Fig. 1. 65

In the drawing, the reference numeral 1, denotes a valve body having a tapering bore 2 for a valve plug or stem 3, which is ported as at 4, and provided with an operating handle 5 and a tension device 6, said tension device maintaining the plug or stem 3 normally seated in the valve body 1 to insure a non-leakable connection between said plug and body. The valve body 1 is also provided with transversely alining or opposed inlet and outlet connections or nipples 7 and 8 adapted to communicate through the medium of the ported plug 3. The elements thus far described with the exception of the outlet connection or nipple 8, are of a conventional form along the lines of a pet cock and form no part of my invention other than valvular means for controlling the supply of gas or other fuel to the outlet connection or nipple 8. 70 75 80

My invention resides in providing the outlet connection or nipple 8 with a conical closure 9 which has its converging walls provided with a series of outlet openings 10 adapted to discharge gas at an angle to the axis of the nipple 8, and that portion of the conical wall between the openings 10 and the extremity of the closure 9 affords an annular valve seat 11, the purpose of which will hereinafter appear. 90 95

The outlet connection 8 may be conveniently referred to hereinafter as an inner nipple, since it is exteriorly screwthreaded as at 12, to receive the nut portion 13 of an outer nipple 14 having a tube 15 terminating in the seat or jet member 16. 100

The outer nipple 14 provides a pressure or velocity regulating chamber 17 adjacent the conical closure end of the inner nipple 14 into which gas is discharged by the openings 10. At the juncture of the chamber 17 and the tube 15, there is an annular shoul-

der or valve portion 18 that confronts the conical valve seat 11 and co-operates therewith in providing a restricted passage between the pressure chamber 17 and the tube 15, and with the outer nipple adjustable on the inner nipple, it is possible to regulate the passage of gas from the chamber 17 into the tube 15 by increasing or decreasing the area of the passage between the valve seat 11 and the valvular portion 18. With the walls of the pressure chamber 17 confronting the conical closure or end of the inner nipple, the chamber 17 tends to retard or baffle the gas admitted by the openings 10, and a further restriction or baffle is incurred by the shoulder or valve portion 18, which being adjustable relative to the inner nipple can regulate the pressure or velocity of gas entering the tube 15.

20 The jet member 16 has a central or axial jet opening 19 and at the base of the jet member or its juncture with the end of the tube 15 there are a plurality of angularly disposed openings or orifices 20 preferably greater in diameter than the central jet openings 19.

The tube 15 is exteriorly screw threaded to accommodate a cap 21 having a nut portion 22 and a central outlet opening 23 in its outer end, said outlet opening being of a sufficient size to receive the extremity of the jet member 16, and with said cap adjustable on the tube 15, the inner end of the outlet opening 23 may be moved to and from the conical surface of the jet member. The conformation of the cap 21 affords a volume or jet regulating chamber 24 and a valve portion 25, the former receiving gas through the openings 20 from the tube 15, and the latter co-operating with the jet member 16 in providing a restricted passage between the chamber 24 and the outlet opening 23. The walls of the chamber 24 tend to retard the emission of gas from the tube 15 and by adjusting the cap 21, the volume and size of the jet of gas from the opening 23 may be easily regulated. The central jet opening 19 will provide a constant supply of gas for a jet of predetermined volume and size, but to this jet may be added additional gas from the chamber 24 and the auxiliary jet openings 20 so that the volume of the jet may be increased to insure proper air injecting in connection with a burner.

55 By adjusting the outer nipple relative to the inner nipple the pressure or velocity of the gas is regulated in the tube 15 and by adjusting the cap 21 on said tube the volume or size of the jet is regulated, and on account of the constructive arrangement of parts, the regulation is made at separable points, which is a desideratum in the manufacture of such valves, insomuch that the pressure of gas being known in one part of the country as different from another part of the country,

it is possible for the manufacturer to adjust the outer nipple relative to the inner nipple so that the valve will properly function under a predetermined pressure. Then, it is optional with the user of the valve to adjust the cap 21 and obtain a jet volume of desired size. However, it is preferable that both adjustments be made by the manufacturer so that a plumber or other artisan, inexperienced in gas pressures, may install the valve without regulating the same.

I am aware that a few valves have been constructed with this end in view, and after thoroughly testing such valves they have been found defective particularly with a low pressure of gas; some of the valves being effective where the gas pressure is from four to eight ounces, but in no instance did I find a valve that would properly function with a pressure from one to eight ounces, whereas my valve has such a wide range of operation and consequently can be safely and economically used with either artificial or natural gas.

I attach considerable importance to the spaced arrangement of the pressure and volume chambers 17 and 24, respectively, particularly the fact that these chambers are about a common axis with a wall of each chamber constituting a valve restricting the outlet of each chamber. This constructive arrangement of parts permits of each part being accurately formed and properly assembled, and there is no danger of an excessive pressure accidentally shifting any of the parts.

What I claim is:—

1. In a gas regulating valve, adjustable structures adapted to have gas pass therethrough and providing longitudinally spaced chambers about a common axis with one of said chambers for regulating the volume therethrough, and an adjustable cap on the other chamber for regulating the pressure of said regulated volume.

2. A gas regulating valve comprising an inner nipple, a chambered outer nipple on said inner nipple, and a chambered cap on said outer nipple, said nipples being in longitudinal spaced relation with each providing co-operating valve parts, with one valve part in advance of the other.

3. A gas regulating valve comprising an inner nipple having a conical apertured closure affording a valve seat between the apertures and the extremity of the nipple closure, an outer nipple on said inner nipple having a valve portion movable to and from the valve seat of said inner nipple so that said inner nipple may be completely closed and an adjustable cap on said outer nipple.

4. The combination of a gas valve having an inner nipple, an adjustable outer nipple, and an adjustable cap, said nipples and said cap having a common axis and all provided

with outlet openings, said inner nipple having an apertured closure extending into said outer nipple and affording a seat to and from which said outer nipple is movable, said outer nipple having a jet member extending into the outlet opening of said cap, and to and from which said cap is movable, and said outer nipple and cap providing nor-

mally communicating chambers one in advance of the other. 10

In testimony whereof I affix my signature in the presence of two witnesses.

HENRY C. MAUL.
